CLAIM

I claim the ornamental design of a drinkware, as shown and described.

DESCRIPTION

FIG. 1 is a front, left, top perspective view of a drinkware showing our new design;

FIG. 2 is a front, left, bottom perspective view of the drinkware of FIG. 1;

FIG. 3 is a left side view of the drinkware of FIG. 1;

FIG. 4 is a right side view of the drinkware of FIG. 1;

FIG. 5 is a front view of the drinkware of FIG. 1;

FIG. 6 is a rear view of the drinkware of FIG. 1;

FIG. 7 is a top plan view of the drinkware of FIG. 1; and,

FIG. 8 is a bottom plan view of the drinkware of FIG. 1. The broken lines in the drawings depict portions of the drinkware that form no part of the claimed design.

1 Claim, 7 Drawing Sheets
